FOOT SIZE MEASURER

Elmer J. Bliss, Boston, Mass., assignor to Regal
Shoe Company, Whitman, Mass., a corporation
of Massachusetts

Application February 25, 1933, Serial No. 658,481

6 Claims. (Cl. 33—3)

This invention is intended to provide a very simple and low-cost device capable of accurately measuring in terms of standard size numbers a human foot for the purpose of fitting 5 shoes.

In an earlier application filed by me June 10, 1932, Serial No. 616,460, I have disclosed a construction of foot size measurer embodying a somewhat similar principle, in which a large 10 sheet metal plate formed the support for a foot gauging and supporting member that was shiftable laterally from place to place to ascertain the length size measurement of the foot being measured, the foot gauging member being 15 provided with removable gauge pieces or members for the purpose of gauging different widths of feet.

The present invention, however, is in the nature of a modification or improvement of the 20 invention forming the subject of the aforesaid application and has certain advantages over the earlier construction in that it greatly reduces the amount of material required for constructing the earlier form and, furthermore, 25 greatly facilitates the length measurement of the foot which is preferably measured with the weight resting on the foot by providing a foot gauging support that does not require shifting to different positions after the weight of the 30 foot is thrown on it, but makes provision for transversely sliding the composite toe gauge member without disturbing the original position of the foot. Furthermore, loss of the removable side gauges is avoided by pivotally attaching the side gauging members, which determine the width measurement of the foot, 35 to the permanent fixed side gauging members projecting upward from the forepart of the foot supporting and gauging member.

40 These and other features of the present invention will be particularly described in the following specification and will be defined in the claims hereto annexed.

In the drawing I have illustrated a simple 45 and convenient form of construction embodying the principles of this invention, in which

Fig. 1 is a plan view of the complete device as it appears in actual use when measuring the length and width of an interposed foot indicated 50 in dotted lines.

Fig. 2 is a side elevation in central longitudinal section of the same construction shown in Fig. 1.

In the practice of this invention as illustrated 55 in the drawing, I provide a foot supporting plate

or member 1, which may be made of sheet metal and which is provided at its rear with an upwardly projecting heel gauging member 2 and is preferably provided at the heel portion with some suitable means for slightly elevating 60 the heel above the forepart of the foot, such as a bolster block 3.

The forepart of the plate 1, that is, the part which underlies the forepart or ball portion of the feet being measured, indicated at 1^a, has upturned side members 4 that diverge in a forward direction to form side gauges for measuring or ascertaining the size width of an interposed foot across the ball of the foot.

It should be understood that according to 70 established practice width size measurement of a normal foot is a function or coordinate of the length size measurement of the foot. To illustrate, the actual ball width of a normal foot that is size 7—C, according to standard practice, will be the same as the actual absolute width measurement of a 6—D foot, or of an 8—B foot. In practice, the unit increment of 75 length size measurement is $\frac{1}{3}$ inch; the unit increment of width size measurement is $\frac{1}{2}$ inch. 80 However, under a standard practice the numerals indicating foot length sizes signify a uniform actual length and a No. 8 foot size length should always be $\frac{1}{3}$ inch longer than a No. 7 foot size measurement. On the other 85 hand, the width size measurement of the foot is a variable whose size designation depends upon the length of the foot being measured and that length may be either the over-all length 90 or the ball length measurement which, according to standard practice, is the straight line distance from the back of the heel to the transverse line intersecting the center of the ball joint of the foot. Accordingly, each size length increase in the over-all length of the foot equals 95 $\frac{1}{3}$ of an inch and involves a corresponding increase in the ball length of the foot equal to $\frac{2}{9}$ of an inch. As width sizes increase by increments of $\frac{1}{2}$ inch, the side members 4, which 100 gauge the width of the foot at the ball, must increase their divergence from any given point $\frac{1}{2}$ of an inch for each $\frac{2}{9}$ of an inch increase in length size of the foot and the side members 4 must be laid out on that ratio.

The fixed side gauges 4 accordingly are laid 105 out to properly gauge feet of different length having the maximum width measurement, which we may assume in this case to be an E width, and therefore these fixed gauges 4 of themselves can only properly gauge feet of different 110

length having that extreme width size measurement. In order, therefore, to determine the size measurement of feet that are narrower it is necessary to diminish the distance between 5 the side gauges in order to form gauging contact with opposite sides of the ball of the foot. Consequently, I attach to the forward ends of the permanent side gauging members 4 supplemental gauging members 5, each $\frac{1}{2}$ inch thick. 10 Any number of these supplemental gauges may be pivoted, one inside the other, to permit them to be swung rearwardly into gauging position. In Fig. 1 I have shown each permanent or outside fixed gauge member 4 provided with two 15 interior supplemental gauge members 5 of the proper width, but any number of such supplemental gauges may be used according to the range of width measurement desired. With all four of these supplemental gauges 5 turned back 20 to gauging position, they would afford a width caliper space four width sizes narrower than when they are all in raised or at inactive position. The actual illustration in Fig. 1 shows a foot being measured that registers 3 $\frac{1}{2}$ length 25 size and also registers a C width, that is two width sizes less than the extreme or greatest width between the fixed members 4. If these two pivotal gauge members, that are in active position, do not form a gauging contact against 30 the ball member of the foot, one of the upstanding gauge members 5 may be swung rearwardly to active position and, if this correctly gauges the width of the foot at the ball then the size measurement indicated would be 35 3 $\frac{1}{2}$ —D.

The foot inserted between the gauges should be retracted rearwardly against the heel gauge 2; the weight of the person should be thrown on the foot to expand it to weight-supporting 40 posture; the pivotal side gauges, if necessary, may be manipulated to determine the width size measurement and then the toe gauge member 7 should be slid along transversely of the foot until one of the toe gauging tabs 7^a forms a gauging contact with the great toe of the foot. The toe gauge plate 7 is provided with a slot 7^b dimensioned to fit the upturned lip 6 of the forward extension of the foot supporting 45 and gauging plate 1 and the forward edge of the toe gauge plate 7 may be provided with an upturned stiffening flange, as shown in 7^c.

With the above described construction not only can the width size and length size measurement of any foot be quickly and easily determined, but there is no need of shifting the foot from place to place to get the correct length measurement and there is no danger of losing the supplemental width gauge members, since they are permanently attached by rivets 55 5^a to the permanent side gauges 4 with sufficient looseness to permit their swinging movement. Outwardly projecting lips 5^b afford a convenient means for lifting the supplemental gauges from active position.

65 It should be understood that the toe gauging tabs 7^a designated by their appropriate length-size number, as measured straight forward from the heel gauge to each tab as it is brought into opposition to the heel gauge member, are arranged in an obliquely offset order at the rear edge of the toe gauge plate 7, each being offset a distance equal to one-half a foot length-size, that is, $\frac{1}{2}$ of an inch beyond the next adjacent tab so as to afford half size length 70 measurements. It will also be understood that 75

in reading the measurement of the foot the width sizes, ranging from A to E on the device actually shown, should always be associated with the length-size measurement of the foot since otherwise the width-size designation standing by itself is meaningless. 80

What I claim is:

1. A foot measuring device for ascertaining the length-size and width-size measurements of a foot comprising a foot supporting member having at its rear end an upward heel positioning member and provided at its forepart with opposed forwardly diverging upturned ball gauging members affording means for indicating width-size measurements of an interposed foot in correlation with its length-size when the foot is positioned against the heel member, and a transversely movable length-size gauge having sliding engagement with guiding means located forwardly of the forepart of the supporting member, said transversely movable member being provided along its rear edge with upstanding tabs adapted to engage the toe of the interposed foot and arranged in a diagonal order to gauge against and measure feet of different length. 90

2. A foot measuring device embracing a foot supporting and heel gauging member, and a forepart provided with means for gauging the ball width of an interposed foot in correlation with the length measurement of said foot, and a transversely movable length gauging member provided at its rear edge with a series of upturned length-size indicating toe-gauging tabs for gauging, respectively, the toes of feet of different length. 100

3. A foot measuring device for measuring in correlation the length and width size measurements of feet comprising a foot supporting member provided at its rear with an upstanding heel positioning gauge and on opposite sides of its forepart area with upturned oblique-ball-gauging members coordinated with a length measuring device comprising a transversely slidable toe-gauging member having at its rear edge toe-gauging means at different size-length distances from the heel gauge and movable by such transverse movement into gauging contact with the toes of feet of different lengths to indicate the length measurement thereof. 115

4. A foot size measuring device embracing in its construction coordinated width-size and length-size gauging members combined with a heel gauging member common to both measuring devices, the toe gauging-member comprising a transversely slidable plate provided with obliquely arranged toe-gauging means along the rear edge of said plate, the width gauging means comprising divergent upstanding ball gauging members on opposite sides of the ball supporting portion of the device, said ball gauging members comprising permanently fixed members to which are pivotally attached, in parallelism therewith, a plurality of side gauging members movable into and out of gauging relation with the ball of an interposed foot. 130

5. A foot measuring device for ascertaining the size-length measurement of a foot comprising a foot supporting and gauging member provided at its rear with an upturned heel-positioning gauge and having a forward extension provided with a guide, and a transverse toe-gauging member provided with a slot having sliding engagement with said guide to permit the toe gauge to be moved transversely of the foot 145 150

supporting member, said toe gauging member being provided at its rear edge with obliquely arranged means for gauging the toes of feet of different length to indicate the length-size measurement of a foot.

6. A foot measuring device for ascertaining in coordination the length-size and width-size measurement of feet embracing a foot supporting and gauging member provided at its rear 10 with an upstanding heel positioning gauge and having upturned integral ball gauging members on opposite sides of its ball supporting portion,

a plurality of movable supplemental gauging plates pivotally connected with the forward ends of said upturned side gauge members, each having a thickness equal to a width-size unit in foot measuring to permit the swinging of one or more of said supplemental gauging members into or out of position for gauging the ball of the foot, and a transversely movable length-size gauging and indicating member for indicating the size-length of the interposed foot being measured.
